CLAIM

The ornamental design for a combined cowboy hat shaped beverage container opener and bottle resealer, as shown and described.

DESCRIPTION

FIG. 1 is a front elevational view of a combined cowboy hat shaped beverage container opener and bottle resealer, showing my new design;

FIG. 2 is front, left, top perspective view thereof;

FIG. 3 is a rear, right, top perspective view thereof;

FIG. 4 is a bottom plan view thereof; and,

FIG. 5 is a rear, right, top perspective view thereof, shown in an alternate environment.

The broken line showing in the drawings is included for illustrative purposes only and forms no part of the claimed design.
